UNITED STATES PATENT OFFICE.

ORREL TOWN LARKIN, OF PLATTSBURG, NEW YORK.

ICE-CRUSHER.

No. 844,146.

Specification of Letters Patent.

Patented Feb. 12, 1907.

Application filed April 13, 1906. Serial No. 311,540.

To all whom it may concern:

Be it known that I, ORREL TOWN LARKIN, a citizen of the United States, and a resident of Plattsburg, in the county of Clinton and 5 State of New York, have invented new and useful Improvements in Ice-Crushers, of which the following is a full, clear, and exact description.

This invention relates to improvements in hand implements for breaking or crushing ice to any desired degree of fineness, the object being to provide a device of this character that will be simple in construction and so arranged that the clogging of fine ice between the breaking or crushing blades will be prevented.

I will describe an ice-crusher embodying my invention and then point out the novel features in the appended claim.

Reference is to be had to the accompanying drawings, forming a part of this specification, in which similar characters of reference indicate corresponding parts in all the figures.

Figure 1 is a perspective of an ice-crusher embodying my invention. Fig. 2 is a sectional view thereof, and Fig. 3 shows a modification.

Referring first to the example of my improvement shown in Figs. 1 and 2, 1 designates the metal head of the implement, to which is secured a socket member 2 for receiving a handle 3, of wood or other suitable material. This socket member 2 is placed 35 in the mold when the head 1 is cast, so that metal of the head may pass through perforations 4 in said socket member, as clearly indicated in Fig. 2.

Extended from the under side of the head 40 are crushing-blades 5, the said blades being spaced apart and provided with cutting-teeth 6. These blades are also placed in the

mold, so that metal of the head may pass through perforations in the blades, as indicated at 7. Between the blades the under 45 side of the head 1 is wedge-shaped or inclined from its longitudinal center outward and upward at both sides, as indicated at 8. By this construction when the device is used for crushing ice the fine particles will be 50 forced outward from between the blades—that is, the packing or clogging of ice between the blades will be prevented.

In Fig. 3 the general construction is similar to that above described, except that the 55 handle 9 is placed at the end of the head, and on the head opposite the blades is a tooth 10, designed for splitting large pieces of ice.

The device shown in Fig. 3 is to be operated by a drawing movement, as the inclines 60 11 extend lengthwise and the blades 12 also extend lengthwise of the head.

It will be noted in Fig. 2 that the teeth or points 6 of one blade alternate with the teeth or points of the adjacent blades, and 65 therefore the ice may be quickly and finely crushed.

Having thus described my invention, I claim as new and desire to secure by Letters Patent—

An ice-crusher comprising a head, the under side of which is inclined upward and outward at opposite sides of its longitudinal center, and blades secured transversely and rigidly in said head, the said blades having 75 perforations receiving metal integral with the head.

In testimony whereof I have signed my name to this specification in the presence of two subscribing witnesses.

ORREL TOWN LARKIN.
